UNITED STATES PATENT OFFICE.

FRANK P. KOBERT, OF MILLDALE, CONNECTICUT.

INSULATOR-BRACKET.

1,169,545.

Specification of Letters Patent. Patented Jan. 25, 1916.

Application filed January 21, 1915. Serial No. 3,588.

To all whom it may concern:

Be it known that I, FRANK P. KOBERT, a citizen of the United States, and residing at Milldale, in the county of Hartford and State of Connecticut, have invented certain new and useful Improvements in Insulator-Brackets, of which the following is a specification, such as will enable those skilled in the art to which it appertains to make and 10 use the same.

This invention relates to insulating devices for use in connecting telegraph, telephone, and other electric wires with a wall, telegraph pole, or other support; and the 15 object thereof is to provide an improved device of this class which is simple in construction, comparatively inexpensive and which may be easily employed wherever devices of this class are required.

The invention is fully disclosed in the following specification, of which the accompanying drawing forms a part, in which the 20 separate parts of my improvement are designated by suitable reference characters in 25 each of the views, and in which:—

Figure 1 is a view showing my improved wire support or holder in the form of a bracket and secured to a wall; Fig. 2 a cross section on the line 2—2 of Fig. 1; Fig. 3 30 a view showing the method of connecting my improved electric wire holder to a telegraph pole or similar device, and; Fig. 4 a section on the line 4—4 of Fig. 3.

In the accompanying drawing I have 35 shown at *a* the wall of a building or other structure, and in the practice of my invention, I provide an electric wire holder or bracket comprising a plate *b* having a plurality of forwardly directed bracket arms *b*², 40 three of which are shown and each of which is provided with an upwardly directed cup-shaped member *b*³ in which is secured a threaded plug *b*⁴ on which, in practice, the ordinary insulator is secured and with 45 which the wires are connected.

In connecting the arms *b*² with the plate *b*, the back of said plate is counter-sunk, so as to form a raised portion *b*⁵ on the front sides thereof and the arms *b*² are provided 50 with necks *b*⁶ which are passed through apertures formed in the raised portions *b*⁵, and which are riveted at the back of the plate *b* to form heads *b*⁷. Between the arms *b*², the plate *b* is provided with longitudinal 55 slots *b*⁸ having raised side flanges *b*⁹ which give strength to said plate, which is stamped

from sheet steel, and said plate is also provided in its opposite sides and adjacent to the ends thereof with short, longitudinal side slots *b*¹⁰ through which are passed pins, 60 bolts or similar devices *c* which are driven into the wall and provided with nuts *c*² and by means of this construction, the plate *b* may be vertically adjusted on the wall within 65 certain limits.

Instead of securing the plate *b* to a wall as shown in Figs. 1 and 2, it may be secured to the cross arm *d* of a telegraph pole *e*, and in this use of the device, the plate *b* is placed in a vertical position, across the 70 front face of the arm *d* and a U-shaped bracket *f* is mounted on the arm *d* and the side portions thereof are provided with threaded extensions *f*² which are passed through the slots *b*⁸ in the plate *b* and provided with washers and nuts *f*³ which bear on the flanges *b*⁹. This construction securely holds the plate in connection with the arm *d* and said plate, or the bracket consisting of the plate *b* and arms *b*² may be 75 adjusted vertically on the arms *d* within certain limits.

The plate *b* of my improved bracket wire support is stamped from sheet metal and at the same operation, the front raised portions *b*⁹ are formed as are also the apertures through which the necks *b*⁶ of the arms *b*² are passed, and at the same time the said 85 plate is provided around the said apertures with raised, radial ribs *b*¹¹ which also serve 90 to strengthen and stiffen said plate.

With this construction, the heads *b*⁷ of the arms *b*² are counter-sunk in back of the plate *b* and do not in any way interfere with the operation of securing said plate 95 to a support, and while I have shown and described the preferred form of my improved wire supporting bracket, my invention is not limited to the exact details thereof, herein shown and described, and changes 100 therein and modifications thereof may be made, within the scope of the appended claims, without departing from the spirit of my invention or sacrificing its advantages.

Having fully described my invention, 105 what I claim as new and desire to secure by Letters Patent is:—

1. A bracket support for electric wires, comprising a plate provided at intervals with counter-sunk back parts and corresponding raised front parts having apertures, and insulator arms provided with 110

necks which are passed backwardly through said apertures and which are riveted to form heads which are flush with the back of said plate, said plate being also provided 5 between said arms with longitudinal slots having forwardly directed side flanges.

2. A bracket support for electric wires, comprising a plate provided at intervals with counter-sunk back parts and corresponding raised front parts having apertures, and insulator arms provided with necks which are passed backwardly through said apertures and which are riveted to form heads which are flush with the back 10 of said plate; said plate being also provided between said arms with longitudinal slots having forwardly directed side flanges, and in the opposite side edge portions and adjacent to the ends thereof with short longitudinal slots.

3. A bracket support for electric wires, comprising a plate provided at intervals

with countersunk back parts and corresponding raised front parts having apertures and insulator arms provided with 25 necks which are passed backwardly through said apertures and which are riveted to form heads which are flush with the back of said plate, said plate being also provided between said arms with longitudinal slots 30 having forwardly directed side flanges, means for securing said plate to a support, said means being provided with threaded members which are passed forwardly through said slots and provided with nuts 35 and washers which bear on said flanges.

In testimony that I claim the foregoing as my invention I have signed my name in presence of the subscribing witnesses this 14th day of January, 1915.

FRANK P. KOBERT.
